GEORGE E. JOHNSON

Lincoln Johnson attorney.

UNITED STATES PATENT OFFICE.

JAMES J. JOHNSON, OF SAN FRANCISCO, AND GEORGE E. JOHNSON, OF FOWLER,
CALIFORNIA.

RUBBER HEEL.

Application filed August 24, 1922. Serial No. 584,010.

To all whom it may concern:

Be it known that we, JAMES J. JOHNSON and GEORGE E. JOHNSON, citizens of the United States, and residents, respectively, 5 of the city and county of San Francisco and of the town of Fowler, county of Fresno, and the State of California, have made a new and useful invention—to wit, Improvements in Rubber Heels; and we do hereby 10 declare the following to be a full, clear, concise, and exact description of the same.

This invention relates particularly to a resilient rubber heel or cushion heel lift.

An object of the invention is to provide 15 a heel formed of inherently resilient material and so constructed and arranged as to afford additional cushioning properties.

A further object of the invention is to provide 20 a resilient heel provided with non-resilient elements embedded therein and through which a plurality of means may be passed for attaching the said heel to a shoe sole in a relatively fixed position.

A further object of the invention is to 25 provide a device that will be superior in point of simplicity, inexpensiveness of construction, positiveness of operation, and facility and convenience in use and general efficiency. Other objects and advantages 30 will appear as this description progresses.

In this specification and the annexed drawings, the invention is illustrated in the form considered to be the best, but it is to be understood that the invention 35 is not limited to such form, because it may be embodied in other forms; and it is also to be understood that in and by the claims following the description, it is desired to cover the invention in whatsoever 40 form it may be embodied.

In the accompanying one sheet of drawings,

Fig. 1 represents a side elevation of a heel constructed in accordance with our invention.

Fig. 2 is an end elevation of Fig. 1.

Fig. 3 is a plan view of Fig. 1.

Fig. 4 is a vertical cross section taken through Fig. 3 on the line 4—4.

Fig. 5 is a perspective view of a heel constructed in accordance with our invention.

In detail, the construction illustrated in the drawings comprises a heel 1 formed preferably of rubber or any other equivalent flexible and resilient composition. The con-

tour and shape of the heel is conventional so as to conform in all respects with the requirements of size and thickness of standard types of heels. The heel comprising our invention differs from the ordinary type 60 of rubber heel in that the body thereof does not lie in a single plane, but the attaching face 2 is dished or concaved while the outer face 3 is bowed or formed convex.

A plurality of nail holes or openings 4 are arranged transversely through the heel extending between the attaching and outer faces. Elongated, non-resilient strips or elements 5, formed preferably of a light 70 sheet metal such as aluminum, are embedded in the heel approximately centrally between the attaching and outer faces, each of said elements having a plurality of holes 6 therein corresponding with and registering with the transverse openings 4 provided in the heel. The non-resilient elements are shaped to assume the same contour as the heel irrespective of the position that the latter assumes.

The outer face 3 of the heel is provided with a peripheral shoulder or raised 7 around a part of its edge, forming additional tread surface and which may be advantageously moulded into any designs or characters for 85 advertising or other purposes.

The rubber heel is attached to a leather, or other equivalent composition sole of a shoe by inserting nails into the holes 4 and driving the same through the corresponding 90 reduced size openings provided in the embedded plates until the heads of the nails would be countersunk with the holes 4 and the heads of the said nails placed in contact with the surface of the embedded elements. 95

All of the nails would be driven home so that the concave face of the heel would lie substantially flush and parallel with the surface of the shoe sole. The nails used for attaching the heel to the shoe sole would be 100 of a gauge substantially equal to the diameter of the holes 6 of the embedded plates so as to tightly and snugly fill the same. Thus, when the heel would be flattened down out of its normal dished shape, a suction grip would be exerted between the peripheral edge of the inner concave face of the heel and outer face of the shoe sole. When fixed by nails to the shoe sole, a secure and binding connection is made, eliminating all 110

of the troublesome faults of placing heels on shoe soles.

Having thus described this invention, what we claim and desire to secure by Letters Patent is:—

1. A resilient heel having a plurality of non-resilient elements embedded therein centrally between the attaching and outer faces and provided with a plurality of openings 10 therein registering with corresponding openings extending to the outer and attaching faces of the heel, said non-resilient elements being arranged in parallel rows extending longitudinally of the heel.
- 15 2. A resilient heel having a plurality of

transverse openings extending therethrough; plural rows of non-resilient elements embedded centrally therein between the attaching and outer faces of said heel and having a plurality of openings therein registering 20 with the corresponding openings in said heel.

In testimony whereof we have hereunto set our hands at San Francisco, California, this 18th day of August, 1922.

JAMES J. JOHNSON.

GEORGE E. JOHNSON. [L. s.]

In presence of—

LINCOLN V. JOHNSON.
